34 Lucy Henry, Mrs.

UNITED STATES PATENT OFFICE.

MARGARET V. WIDHELM, OF FREMONT, NEBRASKA.

HOG-WATERER.

1,350,629.

Specification of Letters Patent. Patented Aug. 24, 1920.

Application filed January 19, 1920. Serial No. 352,249.

To all whom it may concern:

Be it known that I, MARGARET V. WIDHELM, a citizen of the United States, residing at Fremont, in the county of Dodge and 5 State of Nebraska, have invented certain new and useful Improvements in Hog-Waterers, of which the following is a specification.

This invention relates to means for supplying water to hogs and other live stock and has for its object the provision of a sanitary drinking fountain for hogs. Incidental objects of the invention will appear as the description of the same proceeds. 15 The invention is illustrated in the accompanying drawings, in which—

Figure 1 is a perspective view of a watering device embodying my improvements;

Fig. 2 is a transverse section of the same; 20 Fig. 3 is a vertical section taken on the line 3—3 of Fig. 2;

Fig. 4 is a detail perspective view of the watering pan or receptacle.

In carrying out the invention, I employ 25 an outer casing 1 which is preferably cylindrical and is reinforced at its lower end by a ring 2 of angle iron whereby it may rest upon the ground without unduly digging into the same and will sustain the weight of 30 the apparatus. Within this outer casing, I provide a tank 3 which is of such diameter as to provide an air space between itself and the casing and is supported therein by intersecting braces 4 secured to the inner wall 35 of the casing. The tank 3 is provided with a clean-out opening in its bottom which is normally closed by a plug 5 and in the wall of the casing below the tank is an opening 6 normally closed by a slide 7 through which access may be easily had to 40 the plug when it is necessary to clean the tank. The tank is further provided in its top with a vent 8 which is normally closed but may be opened when the tank is to be 45 filled to permit escape of any air which might otherwise be trapped within the tank by the inflowing water. The casing is constructed with a cover 9 which is preferably conical in form, as shown, so that it will 50 amply accommodate the vent 8 and a brace 10 is provided between the top of the tank and the cover 9 to prevent collapse of the cover and consequent injury to the vent. In 55 the cover is provided a filling opening 11 which is located at such point that the vent may be easily reached through the same and

this opening is normally covered and closed by a gate 12 pivoted on the cover and provided with a hooked tongue 13 adapted to engage under a keeper 14 on the cover. A 60 funnel 15 is formed in the top of the tank immediately under the opening 11 and the spout 16 of said funnel extends downwardly in the tank to a point near the bottom of the same, as clearly shown. A screen 17 extends across the funnel 15 to permit water to 65 pass but arrest foreign matter therein.

At diametrically opposite points of the casing 1, I provide hoods 18 which may be of any preferred form and are illustrated 70 as substantially rectangular housings each having an opening 19 in its outer side. A shelf 20 is provided within the housing 18 and a pan or receptacle 21 is placed on and supported by said shelf. The pan fits with- 75 ir. the housing in spaced relation thereto and is provided in its outer side wall with a slot or opening 22. A nipple or spout 23 is provided on the side of the tank and extends through a properly disposed opening 80 in the wall of the casing to admit water to the housing 18, the water flowing around the pan and entering it through the opening 22. Above said opening 22, a horizontal partition 24 is provided within the 85 pan and openings 25 therein permit the water to rise to the space above the partition. Within the housing 18 above the opening 19, I mount a swinging door or guard 27 which will normally extend over 90 said opening 19, as clearly shown in Fig. 2, and this guard should be of such length that its lower edge will impinge against the front wall of the housing below the opening 19 and thereby prevent the guard swinging 95 through the opening.

The walls of the housing are continued below the shelf 20 and a floor or shelf 28 is supported by said walls and the ring 2 as shown in Fig. 2. A heater 29 is supported 100 on each floor or shelf 28 in position to play upon the shelf 20 and prevent freezing of the water in the pan. It will also be noted that the heater is supported above the ground so that it cannot be frozen thereto. 105

In filling the tank, corks or other plugs are placed in the openings 22. The gate 12 is then swung so as to uncover the filling opening 11 and the vent 8 is opened. Water is then poured through the opening 11 into 110 the funnel 15 and will pass through the spout 16 thereof into the tank to fill the same, after

which the vent 8 is closed and the plugs withdrawn from the openings 22 after which the pans 21 are replaced. The water will obviously flow around and into the pans and rise therein until the level thereof covers the nipple 23 thereby sealing said nipple and preventing further flow of the water out through the same. The gate 12 will then be swung to closed position to prevent dust and dirt entering the funnel 15 and the device will be ready for use. An animal desiring to drink will insert his head through the opening 19 and will push the guard 27 upwardly and inwardly, as indicated by the dotted lines in Fig. 2, thereby obtaining access to the water in the pan 21. As the animal withdraws his head after drinking, the guard will, by its own weight swing to the closed position and will protect the water in the pan from the weather, also preventing the entrance of contaminating dust and dirt. As the animal drinks, additional water will flow from the tank into the pan so that a constant supply will be maintained therein 25 as long as water remains in the tank.

It will be readily noted that my stock waterer is very simple in construction and may be produced at a low cost. The pan 21 is easily removable through the opening 19 so that it may be readily cleaned as frequently as may seem desirable, and it will be noted that this pan is complete in itself and of such construction that it will aid in maintaining a sanitary supply of water for 35 the animals.

The animal drinks from the upper portion of the pan and the partition 24 therein prevents him from inserting his head so far that the dirt which may collect in the bottom 40 of the pan will be stirred up. Moreover, the animal cannot get his nose so far below the surface that he will blow the water from the pan or the housing, a sanitary condition in and around the device being thus assured. 45 Any dirt that may possibly be carried into the pan on the animal's head will drain through the openings in the partition 24 and collect in the bottom of the pan whence it may be easily removed through the slot 22 when the pan is withdrawn from the housing 50 for cleaning. When the pan is in the housing, the slot 22 should always be at the outer

side so that any dirt which may be in the pan will not be drawn back into the tank. Inasmuch as the tank is closed on all sides and also protected by the outer casing and the cover thereof, contamination of the water in the tank is not apt to occur but there may be some sediment deposited by the water and occasional cleaning of the tank is desirable. 60 This cleaning of the tank may be accomplished by removing the plug 5 and then flushing the tank through the spout 16 as will be readily understood.

Having thus described the invention, what 65 is claimed as new is:

1. A stock-watering apparatus comprising a tank, a housing disposed at one side of the tank and provided with an opening in its front wall, a shelf in the housing below said opening, a drinking pan removably supported on said shelf and in communication with the tank, and a guard extending across the pan below the upper edges of the walls of the same and provided with an 75 opening.

2. A stock-watering apparatus comprising a casing having a filling opening in its top, a gate arranged to cover said opening, a tank supported within the casing and provided in its top with a vent and with a funnel arranged below the opening in the top of the tank, a clean-out plug in the bottom of the tank, an outlet in one side of the tank, a housing on the casing around the said outlet, and a drinking pan removably supported within said housing and provided with an opening in its outer side wall and having a horizontal perforated partition above said 80 opening.

3. A stock-watering apparatus comprising a casing, a tank supported in the casing, a housing on the outer side of the casing having upper and lower shelves, the space above the upper shelf being in communication with the tank, a pan supported on the upper shelf and provided in its outer wall with an opening through which water may enter or sediment be removed, a perforated horizontal partition in said pan above said 95 opening, and a heater supported on the lower shelf.

In testimony whereof I affix my signature.

MARGARET V. WIDHELM. [L. S.]
